UNITED STATES PATENT OFFICE.

EMANUEL SCHWAB, OF NEW YORK, N. Y.

DESIGN FOR A GLASS CIGAR AND ASH TRAY.

No. 37,977.

Specification for Design.

Patented May 1, 1906.

Application filed March 6, 1906. Serial No. 304,595. Term of patent 7 years.

To all whom it may concern:

Be it known that I, EMANUEL SCHWAB, a citizen of the United States, residing in the borough of Manhattan, city, county, and State of New York, have invented a new, original, and ornamental Design for a Glass Cigar and Ash Tray, of which the following is a specification.

The nature of my design is fully represented in the accompanying drawings, to which reference is made, in which—

Figure 1 is a top view, and Fig. 2 a side elevation, of a tray embodying my design.

I claim—

The ornamental design for a glass cigar and ash tray.

EMANUEL SCHWAB.
